UNITED STATES PATENT OFFICE

2,468,440

ELECTRON TUBE

John Henry Owen Harries, London, England

Application December 26, 1945, Serial No. 637,194
In Great Britain January 4, 1945

3 Claims. (Cl. 250—27.5)

1

The present invention relates to electronic discharge tubes, and, in particular, to discharge tubes suitable for operation at very high frequencies.

It is known that in electronic tubes having a positive grid or equivalent electrode between a cathode and an anode to which an output circuit is connected, secondary electrons are emitted from the anode and that, if during operation the anode potential becomes less than that of the said grid, these secondary electrons tend to travel from the anode to the grid or equivalent electrode. This results in a reduction of the net electron current flowing to the anode, and reduces the efficiency of transfer of energy to the output anode circuit. Furthermore, other undesirable effects are also produced by this backward passage of secondary electrons.

One well known remedy is to interpose between the accelerating electrode and the anode a low potential grid which then prevents the backward passage of secondary electrons. Such a grid is generally referred to as a "suppressor" grid, and was described in Patent Specifications Nos. 1,945,040 and 1,945,041, dated January 30, 1934.

Another method of preventing the backward passage of secondary electrons to the grid is also well known, and was first described in my Patent Specifications Nos. 2,045,525, 2,045,526, and 2,045,527, dated June 23, 1936. This will be referred to as the "critical distance" method.

Combinations of these two principal methods have also been suggested and used. Other methods exist such as the use of specially shaped anodes and anodes having a coating of graphite; but, though on occasions these methods may be combined advantageously with the two principal methods mentioned above, they alone will not, as far as is known, remedy the bad effects of secondary electrons successfully.

The prevention of the undesirable effects of the passage of secondary electrons as distinct from the reduction of the number emitted will be referred to as the process of "suppressing" secondary electrons.

In certain cases, the above remedies involve difficulties which prevent their being employed. For example, in electron tubes operating at very high frequencies, for example, frequencies higher than 3×10^8 cycles per second, it may be very difficult to maintain a suppressor grid at the steady potential which is necessary for it to operate correctly. Moreover, the size and configuration of the tube may be such that it is difficult to introduce a suppressor grid at all. Again, in connection with the "critical distance" method, the distances and spacings necessarily used in tubes intended to operate at extremely high frequencies are sometimes such that it is not possible to place

the anode at or at about the "critical distance."

It will be appreciated, therefore, that up to the present, there has been no way of successfully preventing the deleterious effects of secondary emission, except those previously mentioned, and they are not suitable for use at very high frequencies. In fact, hitherto, it has been considered that, at very high frequencies, secondary electrons cannot well be suppressed at all, and therefore it is common practice to avoid their production by arranging for the beam of electrons not to strike either the anode, or the positive accelerating grid, though it must of necessity pass through the field between them. It is not easy to arrange this, and to do so increases the difficulties of manufacture to a serious extent.

It has now been discovered, during experiments with electron beam tubes, that in certain novel circumstances, the output power need not be adversely affected by the passage of secondary electrons, although no suppressor grid is employed, and the anode is not at the "critical distance" above-mentioned.

One object of the present invention is, therefore, to overcome the deleterious effects of the backward passage of secondary electrons, especially in electron tubes operating at extremely high frequencies, by means not involving the disadvantages of the known methods of suppressing them.

Thus, according to the present invention, an electron valve or discharge tube is arranged to produce one or more beams of electrons, and is furnished with a pair of output electrodes lying in succession in the path of the beam or beams, and with electrode means which can modulate the beam or beams so as to energise an output circuit of which the output electrodes form a part, while the pair of output electrodes are spaced apart by such a distance that, within some part of the ranges of working voltages and frequencies, the transit angle between the pair of output electrodes lies within the optimum range as defined below peculiar to the surfaces and configurations of the pair of output electrodes so that secondary electron emission from the second output electrode is substantially suppressed, and the power output efficiency of the tube is substantially higher than it would be if the transit angle tended to zero. Such a tube may have the stream of electrons formed into a single beam, preferably having a uniform current density over its cross-section. The beam or beams formed should naturally be such that all its constituent electrons have practically the same transit angle between the two output electrodes. In addition, the suppressor action may be substantially assisted by one of the known methods mentioned above; for example, a carbonised anode surface

or a slotted or recessed anode surface or both may be used.

It has now been found in practice that in the case of plane and polished output electrode surfaces, secondary radiation may, particularly if the surfaces are contaminated, increase so much that the maximum efficiency, even at the optimum transit angle, may not be enough for many purposes. It is therefore preferred to reduce the emission of secondary electrons from the electrodes as much as possible, by, for example, coating the surfaces with colloidal graphite or corrugating or slotting them, or using grids or electrodes with grid-like configurations or by utilising more than one of these expedients.

The pair of output electrodes referred to consists of two electrodes located successively in the path of the electron stream, and adapted to form parts of an output circuit, so that during operation, an oscillatory electric field exists between them when the electron beam is modulated. The configuration of each of this pair of output electrodes is such that the electric field between them is substantially bounded and confined by them and does not appreciably extend through them. Of this pair of output electrodes, that through which the modulated electron current first passes is referred to as the "first output electrode," and that to which it then travels is referred to as the "second output electrode" or "anode" and which has a configuration such that at least a substantial part of the electron stream strikes it.

Before explaining more fully the importance of transit angle between the pair of output electrodes in the present invention, it will be convenient to refer to some particular examples of electron tubes according to the invention and methods according to which they may be used and some such examples will now be described in more detail with reference to the accompanying drawings, in which:

Figure 1 is an elevation of an electronic tube, with the output electrode system arranged according to the present invention;

Figure 2 is a plan of the first output electrode seen from below in Figure 1;

Figure 3 is a set of curves showing graphically power output efficiency plotted against transit angle;

Figures 4, 6 and 8 are sectional elevations showing certain alternative configurations of anodes; while

Figures 5, 7 and 9 are plan views of the respective forms; and

Figure 10 is a circuit diagram showing how the novel tube may be utilised.

In the example of an electron beam tube having an output system as illustrated in Figure 1, a beam of electrons travels along the path 1, through the slot 2 in a first output electrode E, to the anode, or second output electrode A. The output electrodes E and A form part of an output circuit, or cavity resonator 3, which is of the concentric line type. The beam of electrons is produced and modulated by means situated within the envelope 4, and although this means may consist of any of many well known devices, a convenient form illustrated in Figure 1 is that described in my patent application Serial No. 409,585, filed September 4, 1941, now Patent No. 2,396,949. As in that prior application, the cathode C, negative grid G1, positive grid G2, deflecting electrodes D1, D2 and electrodes L2 and S are provided and need not be further de-

scribed here. However, the first output electrode E now takes the place of the sub-anode SA in the said prior application.

The anode A (Figure 1) which constitutes the second output electrode is provided with a detachable face 5 which is secured to the back part 6 by screws 7. The anode A as a whole is cooled by water which is arranged to circulate in the inner conductor 8 of the cavity resonator 3 through the inlet and outlet pipes 9, 10. The cavity resonator 3 is constructed in two parts, namely the base 11 and the top 12. The flange 13 on the top 12 is removably bolted to the base 11 by bolts (not shown). The base 11 is water-cooled by water arranged to circulate in the circumferential slot 14 in the base 11. The joints between the flange 13 and the base 11 are made vacuum-tight by causing vacuum wax 15 to flow and which may conveniently be that known by the trade name "Apiezon W.40." Similarly, the glass envelope 4 is made vacuum-tight and attached to the base 11 by means of vacuum wax 16, which may conveniently be that known by the trade name "Apiezon W.100." The assembly 15 will be recognized as one which may be demounted for the purpose of altering the internal arrangements of the apparatus. On reassembling, it may be sealed up and made vacuum-tight by means of the wax 15, 16.

The beam of electrons travelling along the path 1 will travel between the pair of output electrodes through the slot 2 in the first output electrode E, and will strike the anode A.

It will be recognized that if the cavity resonator 3 as a whole is maintained at a steady potential V_b, and if the beam of electrons is modulated at a frequency which is equal to the resonant frequency of the resonator 3, then energy will be delivered from the beam of electrons to the resonator 3, power will appear inside the resonator 3 and may be led out of it into a load by means, for instance, of a loop 22 or other of many well known devices. The apparatus will be recognized as one capable of operating at a very high frequency.

When the pair of output electrodes E and A form part of an output circuit, if a modulated beam of electrons travels along the path 1 and passes through the slot 2 in the first output electrode E to the second output electrode A, then, as already mentioned, power is delivered from the beam to the output circuit which is tuned to the modulation frequency (f) of the beam. The pair of electrodes E and A are maintained at a steady unidirectional potential V_b except for those variations in potential due to the voltage across the output circuit which occurs when power is fed to that circuit.

It is usual to assess the performance of such a system by measuring its power output efficiency

$$(e) = P_o / P_b \quad \text{Equation 1}$$

where

65 P_o=the power output fed to the output circuit from the beam, and

P_b=the direct current power flowing from the source of voltage V_b.

It may be shown that the power output efficiency (e) is a complicated function of a ratio t/T where t is the time taken by a primary electron to pass from the electrode E to the anode A if the beam is not modulated and consequently no power is transferred to the output circuit and

$T=1/f$ and is the periodic time of the modulation frequency of the beam.

If the distance between the pair of output electrodes E, A is d , then

$$t=d/v \quad \text{Equation 2}$$

where v is the velocity of an electron in the unmodulated beam and $=5.95 \times 10^{-7} \sqrt{V_b}$ cms. per second.

The periodic time $T=1/f$ is usually stated as 2π radians. The ratio t/T may then be expressed as what is usually termed a transit angle:

$$\phi=t/T.2\pi=2\pi f.t \quad \text{Equation 3}$$

Then substituting $t=d/v$ and the value of v :

$$\begin{aligned} \phi &= 2\pi f.d/v \\ &= 3.3 \times 10^{-8} \pi f.d/\sqrt{V_b} \end{aligned} \quad \text{Equation 4}$$

It is thus seen that the same power output efficiency (e) can be obtained for any given distance d provided that $f/\sqrt{V_b}$ is maintained constant although the actual values of f and V_b may vary widely. In fact, in theory, there are an infinite number of combinations of different values of d , f and V_b which will yield the same power output efficiency. Any electron tube to provide a given value (e) has therefore to be designed so that these three parameters satisfy Equation 4 for a value of ϕ which corresponds to the particular efficiency (e) desired. The relationship between ϕ and e is complex and, as far as is known, has not yet been clearly stated in the literature and it is not necessary to consider it in further detail here.

Hitherto, however, it has been thought that if ϕ is increased, e will be reduced and will, in fact, fall to a very low value when ϕ is greater than of the order of 2π .

It has also been held hitherto that if the voltages upon both of the electrodes E and A are equal, the presence of secondary electron emission from the second output electrode A when it is struck by primary electrons will reduce the power output efficiency (e) to a very low value at all transit angles (ϕ).

It has now been discovered, however, that if the transit angle (ϕ) lies within a certain optimum range, secondary electrons are suppressed and a good power output efficiency is obtained. The position and extent of this optimum range of transit angles depends upon the nature of the surfaces and configurations of the particular pair of output electrodes E and A which are chosen.

It will be appreciated that the technique of electron tube design, and particularly of those intended to operate at very high frequencies, is such that only certain values of V_b , f and d in Equation 4 can, in fact, be used because considerations of practical design rule out some values. Only certain values of d are, in fact, practical for mechanical and other reasons. For a given desired power output, V_b cannot have other certain values. Other known factors limit the possible values of the operating frequency f . Indeed, in certain electron tubes such as those operating by velocity modulation, the useful values of V_b and f may be closely interlinked so that practically operative values cover only very narrow ranges and the input electrode system is adapted to modulate the electron stream over only a narrow band or bands of frequencies for any given set of operating voltages. Therefore, the present invention can only be applied to tubes in respect of which the operating ranges of volt-

age and frequency are such that a value of d can be determined from Equation 4 which is within practicable limits, when the transit angle ϕ has a value lying within the said optimum range appropriate to the particular pair of output electrodes used, within which range, secondary electron emission is suppressed.

Since the base 11 and the rest of the cavity 3 are in conductive contact and are therefore necessarily at the same potential, it would have been thought hitherto as mentioned above that, secondary electrons produced from the surface of the electrode A where it is struck by the primary electrons, and from the edges of the slot 2 (if any of the electrons strike them) would cause the power output efficiency of the device to be so low as to be almost useless, probably only one or two per cent, or even less.

Nevertheless, for the reasons explained above, in accordance with the present invention, the power output efficiency in fact is arranged to have a useful value by constructing the valve so that the distance d in Figure 1 is such that the transit angle is in the neighbourhood of the optimum value (ϕ_0) at which secondary electrons are suppressed.

It has now been found that the optimum transit angle (ϕ_0) in fact, varies according to the material and configuration of the output electrodes (anode A and the first output electrode E), and therefore that (ϕ_0) can best be found for any one of the many possible materials and configurations stated by one of the following methods.

In following the first method, a special test tube is made which has a mechanically movable anode A. For example, the tube illustrated in Figure 1 may be looked upon as such a test tube. If the assembly is demounted, the anode A may be moved to different positions so as to give different values of d . Apart from any such provisions made to move the anode A, the test tube should preferably be identical with the final tube in which it is desired to utilise the present invention. Test voltages are applied to the anode A and to the output electrode E of the test tube which voltages are preferably equal to or in any case, not widely different from those at which the final tube is to operate. The beam of electrons is produced and modulated at various frequencies over a range which includes the frequency f_0 at which the final tube is to work. The output power efficiency of the test tube is then measured at a number of different distances between the output electrodes and at these frequencies.

A curve is plotted showing the relation between the transit angle ϕ and the power output efficiency (e) as illustrated in Figure 3. As was first shown by the research upon which the present invention is based, this curve will be found to exhibit an optimum range of values of the efficiency (e_0) where it is high compared with its value when the transit angle ϕ tends to zero.

In accordance with the present invention, a final tube is then constructed so that, at an operating voltage V_b of the first output electrode E, and at an operating frequency f_0 , the transit angle is within the optimum range, and therefore secondary electrons from the second output electrode A are suppressed and the power output efficiency is high.

In the second method, instead of using a test tube having movable anodes, a family of test tubes may be used. All of them are to be identical except that the distance between the pair

of output electrodes E and A varies from one tube to another.

The third method is used for the test if, for instance, the means used for modulating the beam in the final tube is such that it will not operate over a range of frequencies. The configurations and materials of the output electrodes E and A must be, of course, identical with those used in the final tube.

In short, the range of optimum transit angles for the nature of surfaces and configuration of a given pair of output electrodes E and A arrived at by means, for example, of the tube illustrated in Figure 1, may be applied to other tubes by the use of Equation 4 in which the materials and configurations of the output electrodes are the same. Utilising this tube as shown in Figure 1, the measurements shown graphically in Figure 3 were made. The parts 5 of the target A were interchanged between those illustrated in Figures 4 to 9.

Curve R was obtained when the surface of the part 5 of the anode A was of polished copper as shown in Figures 4 and 5. It will be observed that a maximum efficiency was obtained of approximately 28% at a transit angle $\phi_0=0.5\pi$ and is much greater than the value when ϕ tends to 0. Final tubes can be made with their respective distance d computed so as to give transit angles with their respective operating values of f and V_b . As previously pointed out such a plane polished copper surface as that of part 5 (Figures 4 and 5) is found to be particularly prone to reduction of the maximum efficiency obtained, even at the optimum transit angle $\phi_0=0.5$, should it, for example, become contaminated by barium from a cathode coating or from a getter. An improvement may be obtained by roughening the surface and/or coating it with colloidal graphite. Care should, however, always be taken to avoid contamination of the surface by any substance of the many known to increase the number of secondary electrons emitted.

Curve S is that for the anode face with its copper surface of part 5 roughened by sandblasting and coated with colloidal graphite as in Figures 6 and 7. It is well known that such treatment will reduce the emission of secondary electrons. The maximum efficiency (e_0) is now about 31%, and again occurs at a transit angle (ϕ_0) = 0.5π and holds over a considerable optimum range.

As previously mentioned, a better power output efficiency, which tends not to be particularly affected by contamination and like defects is produced if the surface of the anode A is recessed or slotted so that most of the electrons in the stream strike that surface at the bottom of the recesses or slots. In exemplification of this, a copper anode (the part 5 in Figures 8 and 9) is used, which is slotted, sandblasted, and coated with colloidal graphite. The high frequency field in the cavity 3 is believed not to extend appreciably into the slots, therefore those electrons which pass into the slots 17 pass substantially out of the field. Curve T in Figure 3 is then obtained. There is a substantial advantage gained by slotting the anode surface inasmuch that a maximum efficiency of as much as 46% is then obtained at a transit angle of (ϕ_0) = 0.3π and is again maintained over a considerable optimum range.

This improved result may be explained by the following hypothesis. Secondary electrons are suppressed in accordance with the present in-

vention because at the instant when they are emitted the electric field at the surface of the anode A (Fig. 5) is directed towards the anode and normally to its plane. This is a result of the time of arrival of the electrons in the stream compared with the variation of the electric field with time. Therefore normally emitted secondary electrons will tend to be returned to the anode by the normally directed electric field; that is, they will be suppressed. Those secondary electrons which are not emitted normally to the anode plane, that is, those which are emitted in directions other than that in which the electron stream travels will not be so readily returned harmlessly to the anode by the electric field and will not therefore be suppressed so effectively. If the surface of the anode is slotted (Figures 8 and 9) so that most of the electrons in the stream strike the surface at the bottom of a slot, then many of these secondary electrons that are not emitted in the direction of the electron stream, but travel sideways when emitted, are caught by the sides of the recess or slot before they travel into the electric field between the anode A and the electrode E and are therefore rendered harmless.

The above results were obtained when the beam of electrons was modulated virtually completely with a sine-shaped wave, and the figures of efficiency refer to that part of the beam of electrons which actually travels through the slot 2 into the interior of the resonant cavity 3.

The surface of the electrode E was sandblasted and coated with colloidal graphite since such treatment was found to be advantageous.

In Figure 3 the parts of the curves marked with crosses are unstable, and of no interest for the present purposes.

It will be appreciated that, in some forms of the invention, the two output electrodes E and A may not necessarily be maintained during operation at the same voltage V_b . For example, in Figure 1, a sheet of mica may be inserted between the base 11 and the flange 13 of the cavity resonator 3 to separate them for direct current voltages, so that the first output electrode E and the anode A may be maintained at differing direct current potentials.

In Figure 10 an example of a connection for a transverse control valve of the kind described in my Patent 2,396,949 is shown. The suppressor grid S is directly connected to the cathode C by a conductor 18. The electrode L2 and the cavity resonator 3, which includes the anode A and the accelerating electrode E, are connected by conductors 19, 20 to a battery B^1 of 2500 volts; the positive grid G2 is connected by a conductor 21 to a tapping at 1400 volts potential in the battery B^1 . The shield grid G1 is connected to a negative biasing battery B^2 . The cathode C is heated by the battery B^3 . The deflection plates D1, D2, are connected through a transmission line T1, T2, to a source G of high-frequency voltage. A beam of electrons produced from the cathode C is transversely deflected during operation by the deflection plates D1, D2, so that it is moved in an oscillatory manner over the bottom surface of the electrode E, so as to produce periodic pulses of electrons through the slot 2. These pulses travel through the slot 2 in the first output electrode E to the second output electrode, or anode A, in the cavity resonator 3. The distance d between the output electrodes (anode A and first output electrode E) is such that at some part of the working range of oper-

ative voltages and operative frequencies of the apparatus, the transit angle between the output electrodes lies within an optimum range over which secondary radiation is substantially suppressed.

Energy is withdrawn from the cavity resonator 3 by means of the probe 22 and fed by a transmission line 23 to an aerial 24.

More than one pair of output electrodes may be used, in accordance with the invention, in 10 a given electron valve.

I claim:

1. An electron discharge device comprising means including a cathode for producing an electron stream, an input electrode system for modulating said electron stream at high frequency, an output electrode located in the path of said stream, a second output electrode located in the path of said stream and spaced from said first output electrode on the opposite side thereof from said cathode, a resonant output system connected between said output electrodes, said second output electrode constituting the principal collector electrode for said electron stream and having a collector surface treated to avoid excessive secondary electron emission resulting from a contaminated metal electrode surface, and said second output electrode being spaced from said first output electrode a distance corresponding to a 25 transit angle between said output electrodes, for a given operating voltage and frequency of operation, of less than about 0.8π radians and is at

or near the maximum of the curve relating output power efficiency of said output resonant system to the transit angle between said output electrodes.

5 2. An electron discharge device according to claim 1 in which the electron receiving area of said second output electrode is formed with relatively deep recesses therein for receiving said electron stream, and wherein the walls of said recesses trap secondary electrons emitted from said second output electrode at angles other than that along which said stream travels.

3. An electron discharge device according to claim 1 wherein the transit angle between said output electrodes lies between 0.25π and 0.7π radians.
